(57) **CLAIM**

The ornamental design for a merchandising system, as shown and described.

DESCRIPTION

FIG. 1 is a front perspective view of a merchandising system.

FIG. 2 is a front elevation view of the merchandising system.

FIG. 3 is a side elevation view of the merchandising system.

FIG. 4 is a rear elevation view of the merchandising system.

FIG. 5 is a top plan view of the merchandising system.

FIG. 6 is a bottom plan view of the merchandising system.

FIG. 7 is a front perspective view of the merchandising system.

FIG. 8 is a front perspective view of the merchandising system; and,

FIG. 9 is a rear perspective view of the merchandising system.

The broken line disclosure is for illustrative purposes only and forms no part of the claimed design.
